UNITED STATES PATENT OFFICE.

LOUIS SCHOTT, OF CINCINNATI, OHIO.

RIVETING JIG.

Application filed May 8, 1924. Serial No. 711,908.

To all whom it may concern:

Be it known that I, LOUIS SCHOTT, a citizen of the United States of America, and a resident of Cincinnati, in the county of 5 Hamilton and State of Ohio, have invented new and useful Improvements in Riveting Jigs, of which the following is a specification.

An object of my invention is to provide a 10 riveting jig for use in mounting handle brackets and the like upon vessels such as sheet iron wash tubs and pails.

Another object is to provide a device of this kind which is simple of construction 15 and operation.

Another object is to provide a device of this kind, the use of which will effect a considerable saving of time and labor.

These and other objects are attained by 20 the means described herein and disclosed in the accompanying drawing, in which:

Fig. 1 is a side elevation of a vessel having a device of my invention mounted thereon for retaining the handle brackets and rivets 25 in position for riveting.

Fig. 2 is a cross sectional view taken on line 2—2 of Fig. 1.

Fig. 3 is a cross sectional view taken on line 3—3 of Fig. 1.

Fig. 4 is a fragmental elevation of a vessel showing the brackets and handle structure.

The device comprises an anvil plate 6 which is in practice given a slightly curved or arcuate working surface to accommodate 35 the inside of the wall 7 of a vessel 8 upon which handle brackets 9 are to be mounted. An L-shaped block 10 is secured centrally at one end of the anvil plate 6 by means of machine bolts 11 or by any other suitable 40 means. The block 10 has a flange 12 which extends parallel to the anvil plate 6 and in spaced relation thereto so that the rounded rim or lip 13 of the vessel wall 7 may be accommodated between the anvil plate and 45 said flange. A pair of spaced arms 14 extend from the flange 12 in alignment therewith and are provided with aligned transverse bores 15. A clamping block 16 having a suitable handle rod 17, is pivotally mounted 50 upon rod 18 which extends through the aligned bores 15 in the arms 14. Suitable pins or lugs 19 extend outwardly from the anvil plate 6 and are adapted to engage the top of the rim 13 of the vessel 8. Thus the 55 jig is placed upon the wall 7 of the vessel with the anvil plate upon the inner side of

the wall and the flange 12 and arms 14 of the block 10 extending over the outer side of the wall 7. The arcuate cam face 20 of the clamping block 16 is positioned eccentric to the rod 18 so that when the clamping block 16 is in the position shown in dotted lines on Fig. 2 the rim and wall of the vessel may be passed between said clamping block and the anvil plate. When the clamping block 16 is turned by means of handle 17 on its eccentric axis the face 20 of the block 16 will engage the outer wall of the vessel. By bringing the handle 17 substantially parallel with the wall 7 of the vessel the jig 60 will be tightly clamped upon said wall. The vessel wall in practice, is provided with rivet holes 21 in which rivets 22 are inserted after which the jig is placed in position in engagement with the heads 23 of all of the 65 rivets required to secure a pair of the handle brackets 9 upon the vessel. The clamping block 16 is then actuated to tightly clamp the jig upon the vessel wall and the rivet heads at which time the handle brackets 9 70 may be placed in position and the riveting operation performed. It should be noted 75 that a plurality of rivets may be inserted in the various rivet holes and may be held securely in position so that the workman may with great efficiency and rapidity 80 perform the necessary riveting operations without having to direct his attention to position the rivet as each one is headed. Having riveted a pair of the handle brackets 9 to 85 the wall of a vessel the handle is readily affixed by inserting a handle 24 between the brackets 9 and inserting a suitable rod 25 through the aligned perforations 26 in the brackets 9 after which the ends 27 of the 90 rod 25 may be spread or riveted.

What I claim is:

1. In a device of the class described the combination with an anvil plate for engaging the inner side of a vessel wall, of a pair 100 of spaced arms mounted in spaced relation to the anvil plate, and a clamping member mounted eccentrically between the arms for engaging the outer side of said vessel wall.

2. In a device of the class described the combination with an anvil plate having a convex riveting surface, a block mounted upon said riveting surface, a flange extending from the block in spaced relation to the anvil plate, spaced arms extending from 110 and in alignment with said flange said arms having aligned perforations therethrough, a

clamping member having a perforation extending therethrough and positioned eccentrically to the clamping face thereof, a rod extending through the aligned perforations in the arms and through the perforation in the clamping block for mounting the clamping block pivotally and eccentrically between said arms, and means carried by the block for moving said block about its eccentric mounting into and out of engagement with the anvil plate.

3. In a device of the class described the combination with an anvil plate for engaging the inside of a vessel wall, a pair of lugs extending from the anvil plate for engaging the top edge of said vessel wall a block mounted on the anvil plate, a flange extending from the block in spaced relation to the anvil plate and the outside of the vessel

wall, and an eccentrically mounted clamping block pivotally mounted on the flange for engaging the outside of the vessel wall.

4. In a riveting jig the combination with an anvil plate for receiving a vessel wall having rivets extending therethrough, lugs extending from the anvil plate for engaging the top of the vessel wall whereby the anvil plate is suspended in position over the rivets, a flanged block extending about the top and outside of the vessel wall, and clamping means mounted on the block for engaging the outside of the vessel wall whereby rivets are securely held in position in rivet holes in the vessel wall.

In testimony whereof, I have hereunto subscribed my name this 30th day of April, 1924.

LOUIS SCHOTT.
